CLAIM

(52) **U.S. Cl.**

The ornamental design for a teach pendant bumper, as shown and described.

USPC **D14/440**

(58) **Field of Classification Search**

DESCRIPTION

USPC D14/250, 440, 447; 206/45.23, 320,
206/45.2, 316.2; 361/679.55; 294/25;

FIG. 1 is a perspective view of a teach pendant bumper that has an unclaimed back strap;

224/218; D9/414
CPC G06F 1/1628; G06F 1/1613; G06F 1/1626;

FIG. 2 is a left side elevational view of the teach pendant bumper of FIG. 1;

A47B 23/044

FIG. 3 is a right side elevational view of the teach pendant bumper of FIG. 1;

See application file for complete search history.

FIG. 4 is a rear side elevational view of the teach pendant bumper of FIG. 1;

(56) **References Cited**

FIG. 5 is a front side elevational view of the teach pendant bumper of FIG. 1;

U.S. PATENT DOCUMENTS

FIG. 6 is a top plan view of the teach pendant bumper of FIG. 1; and,
